UNITED STATES PATENT OFFICE.

WILLIAM S. TOTHILL, OF CHICAGO, ILLINOIS.

AMUSEMENT-SLIDE.

No. 909,480.

Specification of Letters Patent.

Patented Jan. 12, 1909.

Application filed July 8, 1908. Serial No. 442,600.

To all whom it may concern:

Be it known that I, WILLIAM S. TOTHILL, a citizen of the United States, residing at Chicago, in the county of Cook, State of Illinois, have invented certain new and useful improvements in Amusement-Slides, of which the following is a specification, reference being had to the accompanying drawings.

This invention relates to improvements in amusement slides and particularly to the means for attaching the slide proper at the upper end thereof to the supporting standard or frame. It has been customary to make the slide proper of these devices of wood,— preferably of hard wood,—and highly polished. It is in such cases of course necessary to protect such surfaces from the weather in one way or another, and this has been accomplished by making the upper end of the slide proper detachable from its support so that the slide might be disconnected and placed in an inverted position. To attain this end, hooks have been provided for the upper end of the slide proper which have engaged a rod passing transversely across the support for said upper end. The work of attaching or detaching the slide from its support has required at least two men, the device being necessarily made quite heavy to get the required strength.

It is the object of this invention to provide improved means for attaching the heavy slide to its support, which attaching means may be as perfectly safe and durable as the old attaching means, and by the use of which the slide proper may be rendered capable of being turned over by one person without trouble. I accomplish this object by the means shown in the drawings and hereinafter specifically described.

What I claim to be new will be pointed out in the claims.

In the accompanying drawings:—Figure 1 is a perspective view of the complete apparatus. Fig. 2 is a perspective view of the same apparatus with the slide proper and its lower support inverted. Fig. 3 is an enlarged detail, being a longitudinal section through the upper portion of the slide proper, and showing some of the parts of the standard that supports said upper end. Fig. 4 is an enlarged detail, being a perspective view of the connecting part shown in Fig. 3. Fig. 5 is an enlarged detail, being a longitudinal section through the upper portion of the slide proper at the side opposite

that at which Fig. 3 is taken, and likewise showing parts of the supporting standard. Fig. 6 is a detail, being a section on line 6—6 of Fig. 5.

Referring to the several figures of the drawings, in which corresponding parts are indicated by like reference characters:—10 indicates the usual well-braced standard supporting the upper end of the slide proper, of ordinary step-ladder construction, the top step of which is indicated by 11.

12 indicates the ordinary guard at each side.

13 indicates the slide proper, supported at its lower end by a frame 14, or in any other suitable manner. In the construction shown, the frame 14 is rigidly attached in any suitable manner to the under side of the slide 13.

The parts so far described are of ordinary construction and form no part of my present invention, and are therefore not described in detail.

Referring now to the means for attaching the upper end of the slide 13 to the standard 10, 15 indicates a metal plate, terminating at one end in a rod 16 screw-threaded at its end. The plate 15 in the construction shown is secured to the step 11 by means of bolts 17. As shown in Figs. 3 and 4, the rod 16 and plate 15 are at an angle to each other, so that said rod 16 is inclined downward from said step.

Suitably attached to the under side of the slide 13 at its upper end is a block which in the construction shown is composed of two parts 18 and 19,—preferably of wood, through one end of which block 18—19 is bored a hole through which the rod 16 passes. Upon the screw-threaded end of the rod 16 is then placed a nut 20, by means of which the slide 13 may be drawn up as close to the step 11 as may be desired. As a precaution against the nut's being accidentally removed, I provide a hole through the rod 16 below said nut and pass a cotter 21 through said hole.

Near the end of the step 11 opposite that to which the plate 15 is attached, there is secured to the under side of said step 11 a tapered block 22 and metal plate 23, which serves as a rest for the slide 13, being secured in place in the construction shown by means of bolts 24. The plate 23 is given a slight bend at the edge of the block 22 so that the lower end of said plate has the same inclination as that of the rod 16. With the slide 13

in the position shown in Fig. 5, it is seen that the part 19 of the block 18—19 rests securely upon said plate 23 at the side of the slide 13 opposite that supported by the rod 16. To hold said slide 13 firmly in position, I provide a clamp in connection with the plate 23. Near the lower end of said plate below the block 18—19, is provided a hand-lever 25, one end of which is curved, as shown in Fig. 5, to bring its end in register with the under side of the part 18 of the block 18—19, which part 18 is cut away, as shown in Figs. 5 and 6, to permit the curved end of the hand-lever 25 to be moved over the part 19 of the block 18—19, thus holding the slide 13 to which said block is attached firmly in position on said rest 23.

From the foregoing description, it will be evident that when the slide is in use, the parts will be very securely held in place, and that when it is desired to cease using the slide it is a very little matter to turn the hand-lever 25 to free it from the block 18—19 and to take hold of the lower end of the slide and turn the slide and standard 14 over on the pivot rod 16. The slide is provided with a curve at 26 which is so proportioned with relation to the height of the standard 14 and the inclination of the slide 13 that, with the slide 13 in inverted position and with the end thereof resting on the ground, the upper end of the slide has the same inclination as when in normal position ready for use, so that the turning of the slide on the pivot rod 16 is accomplished easily and without undue strain on the apparatus.

While I have described the parts 15 and 23 as metal plates, it will be understood that that is merely the way I prefer to embody my invention, and I do not restrict myself to that particular construction. Nor do I restrict myself to a block composed of two pieces 18 and 19 attached to the under surface of the slide 13, as any other desired construction may be used.

My invention includes generically the subject-matter of the broader claims and is not restricted to the details of construction shown except as hereinafter specifically claimed in detail.

So far as I am aware, no one in the art has heretofore provided a construction in which the slide has been adapted to be turned or

rotated transversely while still connected to the support for the purpose of inverting it, and this feature is accordingly claimed broadly.

What I claim as my invention and desire to secure by Letters Patent is:—

1. In an amusement slide, the combination of a support and an inclined slide connected therewith and adapted to be inverted transversely while still connected to said support.

2. The combination of a slide curved at one end, a standard secured to the under side of said slide near the curved end thereof, a relatively higher support for the other end of said slide, and a pivotal connection between the upper end of said slide and said support adapted to permit said slide to be turned on a longitudinal axis.

3. The combination of an inclined slide, a support for the upper end thereof, means pivotally connecting the upper end of said slide at one side with said support, a rest on said support for the other side of said slide at its upper end, and means for holding said slide in contact with said rest.

4. The combination with an inclined slide, a support for the upper end thereof, a block secured to said slide at its upper end, said block having an opening through it near one end, and a pivot rod secured to said support at one side thereof and entering said opening, means for preventing pivotal movement of the slide on said rod.

5. The combination with an inclined slide, a support for the upper end thereof, and a pivotal connection between said slide and said support, of a block secured to the under side of said slide at its upper end, a rest secured to said support for said slide at one side of the pivotal connection, a hand-lever pivoted to said rest below said block, and a shoulder on said block adapted to be engaged by one end of said hand-lever to lock said slide on said rest.

6. The combination with a support, and an inclined slide, of a pivot rod connecting said slide and said support, said pivot rod extending longitudinally of the slide.

WILLIAM S. TOTHILL.
